KITCHEN FAUCET SPOUT

James E. Niemann, Louisville, Ky., assignor to American Standard Inc., New York, N.Y., a corporation of Delaware

Filed Nov. 18, 1969, Ser. No. 20,169

Term of patent 14 years

Int. Cl. D23—01

U.S. Cl. D23—32

FIG. 1 is a side elevational view of a kitchen faucet spout embodying my new design;

FIG. 2 is a top plan view thereof;

FIG. 3 is a front elevational view thereof; and

FIG. 4 is a perspective view thereof.

I claim:

The ornamental design for a kitchen faucet spout, substantially as shown.
